UNITED STATES PATENT OFFICE.

SIMON CARLIN, OF PHILADELPHIA, PENNSYLVANIA.

DESIGN FOR A RING, BRACELET, BREASTPIN, BUCKLE, OR SIMILAR ARTICLE OF JEWELRY.

53,195.

Specification for Design. Patented Apr. 15, 1919.

Application filed November 20, 1918. Serial No. 263,434. Term of patent 7 years.

To all whom it may concern:

Be it known that I, SIMON CARLIN, a citizen of the United States, residing in Philadelphia, in the county of Philadelphia and State of Pennsylvania, have invented a new, original, and ornamental Design for Rings, Bracelets, Breastpins, Buckles, or Similar Articles of Jewelry, of which the following is a specification, reference being had to the accompanying drawing, forming a part thereof.

Figure 1 of the drawing is a perspective view of a ring showing my new design, and Fig. 2 is a side elevation of the ring, also showing my new design.

I claim:

The ornamental design for a ring, bracelet, breast pin, buckle, or similar article of jewelry, as shown.

SIMON CARLIN.
